T. Early,
Bedstead Attachment,
No 1,062, Patented Jan. 8, 1839.

UNITED STATES PATENT OFFICE.

THOMAS EARLY, OF WILLIAMSON COUNTY, TENNESSEE.

MODE OF ATTACHING CURTAIN-POSTS TO BEDSTEADS.

Specification of Letters Patent No. 1,062, dated January 8, 1839.

To all whom it may concern:

Be it known that I, THOMAS EARLY, of the county of Williamson, in the State of Tennessee, have invented a new and Improved

5 Mode of Adding to or Combining with the Common Bedstead Curtain-Posts; and I do hereby declare that the following is a full and exact description.

The nature of my invention consists in so 10 attaching a connecting curtain post to the common bedstead, that the covering of the bed may hang over the bedstead on all sides without the interference of the curtain posts, uniting taste with convenience.

15 To enable others to make and use my invention, I will proceed to describe its construction.

It consists simply in attaching or connecting the curtain posts *a a* to the feet of the 20 bedstead posts *b, b* by staples *c, c*, the shanks or prongs of the staples entering the lower

ends of the posts, so that all the posts shall stand firm on the floor. The curtain posts standing from 2 inches to 6 inches or farther directly off from the corners of the bed- 25 stead. The testers or curtain rails should be confined on the curtain posts by strong screws to keep the posts firm and steady. The curtain posts are distinct pieces from the posts of the bedstead, and only connect- 30 ed therewith as above described and as may be seen from the drawing hereto annexed.

What I claim as my invention, and desire to secure by Letters Patent, is—

The adding to, or combining with the 35 common bedstead curtain posts, as above described.

THOMAS EARLY.
